UNITED STATES PATENT OFFICE.

FRANK P. WEST, OF ORTING, WASHINGTON.

CORN-RACK.

1,078,814.

Specification of Letters Patent.

Patented Nov. 18, 1913.

Application filed May 4, 1912. Serial No. 695,196.

To all whom it may concern:

Be it known that I, FRANK P. WEST, citizen of the United States, residing at Orting, in the county of Pierce and State of Washington, have invented certain new and useful Improvements in Corn-Racks, of which the following is a specification.

This invention relates to racks for seed-corn, and has as its object to provide a rack which will occupy but little space and yet will be adapted to support a maximum number of ears.

The invention further aims to provide a rack for seed-corn so constructed that it will be adapted to support the ears of seed-corn without injuring the kernels.

For a full understanding of the invention reference is to be had to the following description and accompanying drawing, in which:

Figure 1 is a view in elevation of the rack embodying the present invention. Fig. 2 is a horizontal sectional view on an enlarged scale on the line 2—2 of Fig. 1. Fig. 3 is a perspective view showing one of the ear supporting members. Fig. 4 is a similar view illustrating a similar modification of the member shown in Fig. 3.

Corresponding and like parts are referred to in the following description and indicated in all the views of the accompanying drawing, by the same reference characters.

In the drawing the rack is illustrated as comprising a frame consisting of end-stands 1, secured at their lower ends to suitable bases 2. An intermediate standard 3 is provided and is supported at its lower end by a base 4 and a cross-piece 5 is secured to the upper ends of the standards 1 and 3 and serves to connect the standards in spaced relation. To the inner face of each standard 1 is secured a bar 6 into which, at intervals, are driven nails or other suitable securing devices 7. Wires 8 are secured at their ends to nails 7 and are stretched taut between the standards 1 and these wires are engaged by staples 9 upon the standard 3 as shown in Fig. 1 of the drawing. The wires 8 extend parallel to each other, and horizontally, and are braced in proper spaced relation by means of vertically extending tie-wires 10, which are secured at their upper ends to the cross-piece 5 and are secured to the wires 8 at their points of intersection therewith by solder or other means.

The invention contemplates the provision of ear supporting members which are designed to be hung upon the wires 8 and support the ears of corn, and these members may be either of the form shown in Fig. 3 60 or of the form shown in Fig. 4 of the drawing. The member shown in Fig. 3 is formed from a suitable length of wire which is bent to substantially annular form and is indicated by the numeral 11. The end-portions 65 of this wire are bent as indicated at 12 and the said portions are bent to hook form, as indicated at 13.

By referring to Figs. 1 and 2 of the drawing, it will be observed that the ear of corn 70 to be supported has its butt end encircled by the member 11 and that the hooked ends of this member are engaged with one or another of the wires 8 at points between two adjacent wires 10.

It will be readily understood by referring to Fig. 2 of the drawing that the ears of corn may be hung upon both sides of the rack. In other words, two ears may be supported from that portion of each wire 8 80 which extends between two adjacent wires 10.

The ear supporting member shown in Fig. 4 of the drawing is also formed from a length of wire which is bent to annular form and is indicated by the numeral 14 and this wire has one end bent to form a hook 15 and has its other end bent or twisted around the shank of the hook as at 16. This member is employed in substantially the same way as the member shown in Fig. 3, the ear of corn being supported in the loop 14 and the hook 15 being engaged with one or another of the wires 8.

From the foregoing description of the invention it will be seen that there is provided a corn rack which is simple in construction, inexpensive to manufacture and which will support a maximum number of ears of corn in a small space and in such manner that the useful kernels will not be injured.

Having thus described the invention what is claimed as new is:—

A drying rack comprising a frame, said frame including horizontal strands, vertical strands intersecting the horizontal strands, ear-supporting members pivotally mounted on the horizontal strands, said ear-supporting members being disposed in pairs and consisting of substantially circular ear-embracing portions and being terminally looped 110

to embrace the strands, the ear-supporting members of each pair being disposed with their looped terminals in contact, the ear-supporting portion of one of the members extending on one side of the horizontal strand and the ear-supporting portion of the other member extending on the other side of the horizontal strand whereby the

ears which are supported come in contact and maintain themselves in vertical position. 10

In testimony whereof I affix my signature in presence of two witnesses.

FRANK P. WEST. [L.S.]
